(57) **CLAIM**

I claim, the ornamental design for a golf putter, as shown and described.

DESCRIPTION

FIG. 1 is a perspective view of a golf putter showing my new design;

FIG. 2 is a rear elevational view thereof,

FIG. 3 is a front elevational view thereof,

FIG. 4 is a left side elevational view thereof,

FIG. 5 is a right side elevational view thereof,

FIG. 6 is a top plan view thereof;

FIG. 7 is a bottom plan view thereof; and,

FIG. 8 is an enlarged elevational view taken on breakout circle 8 of FIG. 3.
